J. Holley,

Blow Pipe,

No 19,636.

Patented Mar. 16 1858.

UNITED STATES PATENT OFFICE.

JOSEPH HOLLELY; OF NEW YORK, N. Y.

IMPROVEMENT IN BLOW-PIPES.

Specification forming part of Letters Patent No. 19,636, dated March 16, 1858.

To all whom it may concern:

Be it known that I, JOSEPH HOLLELY, of New York, in the county of New York and State of New York, have invented a new and Improved Blow-Pipe; and I do hereby declare that the following is a full and exact description thereof, reference being had to the accompanying drawings, making part of this specification—

Figure 1 being a longitudinal vertical section in the center of the blow-pipe arranged in proper position, together with all accompanying apparatus; Fig. 2, a longitudinal section of a portion detached, showing certain parts differently arranged from their position as represented in Fig. 1; Fig. 3, a similar section of the same portion, exhibiting a still different position of the said parts; Fig. 4, a vertical section of another part or portion detached at right angles to the section of the same part shown in Fig. 1.

Like letters designate corresponding parts in all the figures.

My improved blow-pipe is of that kind of blow-pipes in which the blast is produced by a jet of steam generated in a suitable boiler or generator, the steam being itself inflammable, as that of alcohol, and thereby increasing the intensity of the heat, or uninflammable, as that of water.

A suitable stand or frame, A, having been provided, the boiler or generator B is placed thereon, so as to admit the application of a lamp, C, beneath it, for the purpose of heating the liquid therein, in order to produce the steam. On another part of the stand another lamp, D, is so situated as to receive the jets of steam through its flame to create the necessary heat required in the various uses of blow-pipes. In order to adjust the flame of the lamp D to the exact height desired for receiving the jets properly, it may have a wick-tube adjustable up and down by means of a device clearly represented at *w* in Fig. 1.

To insure safety and the desired variation of pressure, a safety-valve is required to be attached to the boiler. I employ an improved safety-valve for the purpose, of the following construction:

The form of the valve E may be the ordinary conical, and it may rest in a seat, G, of no unusual construction, to be screwed or other-

wise attached air-tight to the top of the boiler. The aperture in which the valve-seat is inserted may also serve the purpose of pouring the fluid through into the boiler. From the lower surface of the valve seat G project downward two parallel rods, *b b*, substantially as shown, which serve as guides to keep a sliding bar, *c*, in place. Between this bar and the valve-seat is situated a spiral spring or its equivalent, *d*, which embraces the projecting stem *a* of the valve. The valve-stem has a screw-thread, *f*, which enters a corresponding screw in the bar *c*, as represented. The upper end of the valve terminates in a flattened or milled head, for grasping with the fingers to turn the valve. Thus by turning the valve itself one way or the other the bar *c* is raised or lowered, and consequently the force of the spring *d* is increased or diminished at pleasure, thereby varying the amount of pressure allowed to the steam in the boiler. By this employment of the valve itself for its own regulator, not only is the whole made more simple and cheap, but it is less liable to derangement, and is more readily managed. To obviate any liability of the aperture round the valve-stem being stopped by the spring *d*, side branching holes, *g g*, Fig. 4, may be made to allow a free discharge of the steam.

Into the top of the boiler is inserted a faucet-seat, H, with a bent passage, *h*, as represented. Over the mouth of this seat the barrel I of the faucet is screwed or otherwise secured. Two jet-pipes, M N, project from the faucet-barrel, substantially as represented, the orifice *t* of one being larger, and the other orifice, *u*, being very fine, for producing the finest jet possible. The inner end of the barrel has three apertures, *i l m*, situated in a row, as shown in the drawings. The outer end of the barrel has only two apertures, *n o*, situated, respectively, opposite to the upper and lower apertures, *i m*, in the inner end of the faucet-barrel and communicating, respectively, with the two jet-pipes. The spigot or key L of the faucet has three perforations, *p r s*, the perforation *p* communicating horizontally or directly between the two upper opposite apertures, *i n*, of the faucet-barrel, the perforations *s* communicating in like manner between the two lower opposite apertures, *m o*, and the other perforation, *r*, communicating between

the lower inner aperture, m , and the upper outer aperture, n , of the barrel. The upper and lower perforations, p s , are at right angles (or at equivalent angles) to each other, and the middle perforation, r , is parallel with either the lower perforation, s , as represented in the drawings, or with the upper perforation, p . Thus arranged, when the key L is situated as represented in Fig. 1, the middle perforation, r , opens a communication between the middle inner aperture, l , and the upper outer aperture, n , while the lower perforation, s , opens a direct communication between the inner and outer lower apertures. Thus jets of steam are projected simultaneously from both jet-pipes whenever a double jet may be required. Then by turning the key L half a revolution the middle perforation, r , will be closed, while the lower aperture, s , will still offer a direct communication between the two lower apertures, m o , as represented in Fig. 2, so that only the lower or fine jet-pipe, N , will project a jet. By turning the key L one-fourth of a revolution from either of the positions shown in Figs. 1 and 2, or in the position shown in Fig. 3, both the middle and lower perforations will be closed, and the upper perforation, p , will open a direct communication between the inner and outer apertures, i and n , and thus allow a jet only to be projected from the upper coarser jet-pipe, M . By this simple arrangement, therefore, either jet or both jets together may be used at pleasure. By turn-

ing the key about one-eighth of a revolution from either of the positions above described, both jets will be stopped.

The arrangement of the faucet-seat H on the top of the boiler prevents the accumulation of condensed steam there, and thus renders the jet always pure; and by having the faucet as far from the boiler as convenience will allow and as near the flame of the lamp D as the heat thereof will permit, together with the situation of the faucet-seat at the top of the boiler, a finer, longer, steadier, and purer jet is produced, as I have ascertained by repeated experiments.

I disclaim all arrangements of blow-pipes substantially different from that above described.

What I claim as my invention, and desire to secure by Letters Patent, is—

A blow-pipe provided with a faucet, I , spigot L , and jet-pipes M N , constructed and arranged as described, in connection with a safety-valve, E , arranged and operating in the manner set forth, for the purposes herein specified.

The above specification of my improved blow-pipe signed by me this 6th day of February, 1858.

JOSEPH HOLLEY.
